UNITED STATES PATENT OFFICE.

JOHN A. BIDWELL, OF PHILADELPHIA, PENNSYLVANIA.

HAMMOCK.

SPECIFICATION forming part of Letters Patent No. 552,229, dated December 31, 1895.

Application filed October 1, 1895. Serial No. 564,300. (No model.)

To all whom it may concern:

Be it known that I, JOHN A. BIDWELL, a citizen of the United States, residing at the city of Philadelphia, in the county of Philadelphia and State of Pennsylvania, have invented certain new and useful Improvements 5 in Hammocks, of which the following is a specification.

The principal object of my present invention is to provide simple, durable, and efficient means for connecting the bed or body of a hammock, with its suspension-rings, in such manner that a continuous cord may be first looped back and forth and connected with 15 the corresponding suspension-ring and then applied to the hammock bed or body and in such manner that the weight or load upon the hammock bed or body is well distributed between the various loops that radiate from the 20 suspension-rings.

To this end my invention consists in the improvements hereinafter described and claimed.

The nature, characteristic features, and 25 scope of my invention will be more fully understood from the following description, taken in connection with the accompanying drawings, forming part hereof, in which—

Figure 1 is a perspective view of a hammock 30 embodying features of my invention. Fig. 2 is a sectional view taken in the direction of the warps of the body of the hammock and showing a loop of the suspension-cord connected therewith. Fig. 3 is a view showing 35 the suspension-loops before their application to the body or bed of a hammock and illustrating the same as comprised of a continuous cord looped back and forth onto a suspension ring or eye. Fig. 4 is a view illustrating the 40 manner of looping the suspension-loops and showing the same with the hammock bed or body removed. Fig. 5 is a view of one of the suspension-eyes and portions of the suspension-cord in a completed state, and Fig. 6 is 45 a detail view.

In the drawings, *a* is a hammock bed or body which may comprise a woven web and which is hemmed at its ends, as at *b*, Figs. 1 and 2, by means of stitches *c*.

50 In Figs. 3 and 4, *d*, *d'*, *d²*, *d³*, *d⁴*, *d⁵*, *d⁶* and *d⁷* are a series of loops radiating from a suspension-ring *e* and formed from a continuous

cord *ff'*. One end *f* of this cord is tied or secured to the suspension-ring or eye *e*. It is then led off and back, Fig. 3, through the ring 55 or eye *e*, so as to form the loop *d*, which loop terminates in the bight *g*, and this operation is repeated to form as many additional loops as are required. Upon the completion of the last loop the end *f'* of the cord is tied across the 60 other loops, as indicated in Fig. 4, and shown in Fig. 5. Obviously the cord may be rapidly applied to the ring in the manner above described even by unskilled labor, whereby economy in production is insured. The bight 65 *g* of the loop *d* is passed or inserted into the open end of the hem *b*. The bight of the loop *d'* is passed through the web of the body or bed and inserted through the bight of the loop *d* and then into the hem *b*, and each of the loops 70 of the series is similarly applied, whereupon the last one *g'* that enters the hem is secured to the remaining bight *g²*—for example, by means of a clip *h*, Fig. 6, or knot *h*, Fig. 4. The bights *g* of the various loops are readily 75 passed through the hem and through each other in the manner above described—for example, by means of a needle—without requiring any considerable expenditure for labor and with the production of an exceedingly 80 neat and attractive appearance in the finished article.

Since the loops are all strung together and passed through portions of the hem, it follows that a load upon any portion of the bed or 85 body is evenly distributed among the loops, because the bights of the latter may slip in respect to the loops that pass through them and thus effect a distribution of the load upon them.

If desired, a stretcher *i* may be inserted in the hem *b* at one or both ends of the hammock and secured therein by sewing up the ends of the hem or otherwise. However, the stretcher may be dispensed with.

Having thus described the nature and objects of my invention, what I claim as new, and desire to secure by Letters Patent, is—

1. The herein described improved means for securing a hammock bed or body to its suspension eye which comprise the combination of, a hem at the end of the bed or body, with, bights of cord radiating from the eye and inserted into and part way through said hem

and movably strung together by passing one through the other, for the purposes set forth.

2. The herein described improved means for securing a hammock bed or body to its suspension eye which comprise the combination of, a hem at the end of the bed or body, a continuous cord attached between each of its bights to the eye and having its bights run into and part way through the hem and mov-

ably strung together by passing one through to the other, for the purposes set forth.

In testimony whereof I have hereunto signed my name.

JOHN A. BIDWELL.

In presence of—
A. B. STOUGHTON,
K. M. GILLIGAN.
